INFANT'S BIB AND AUXILIARY TRAY

John H. Klaine, West Palm Beach, Fla.

Application January 21, 1955, Serial No. 483,283

6 Claims. (Cl. 2—49)

This invention relates to children's bibs and tray covers and consists more particularly in new and useful improvements in a combined infant's bib and auxiliary tray adapted for use in connection with the conventional tray of a child's highchair, a dining table or any suitable flat supporting surface, to prevent the spilling of food or the dropping of toys on the floor. Those familiar with the raising of children, well know the difficulties encountered particularly at feeding time, in avoiding the splashing or spilling of food both on the clothing of the child and on the floor, when an infant is feeding himself or being fed while seated in a conventional highchair. An object of the invention is to avoid these difficult problems by providing an integral bib and tray construction designed to protect the child's clothing and also to confine food and utensils to the area immediately in front of the child.

Another object of the invention is to provide in a combination of this type, an auxiliary tray structure having a bottom bounded at its front and side portions by an upstanding, inflatable marginal wall, said bottom being formed of flexible plastic material which serves as a main tray cover and terminates at the rear of the tray in an extended integral bib portion. The tray is adapted to serve as an auxiliary receptacle which rests upon the conventional tray of a child's highchair or other flat supporting surface with the bib portion extending rearwardly and secured over the child's chest and around his neck in the usual manner.

A further object of the invention is to provide an integral bib and auxiliary tray having inflatable, tubular side walls which in use, serve to form a confining basin or receptacle which may readily be collapsed for storage or shipping.

A still further object of the invention is to provide a device of this character in which the component parts are secured together entirely by heat-sealing, so as to avoid the use of stitches or seams which have a tendency to collect waste particles of food.

Still another object of the invention is to provide an integral bib and tray structure designed to give the child complete freedom of movement, but at the same time to more readily intercept and retain scattered particles of food when used at feeding time, or playthings and toys which so frequently are dropped or knocked off of the child's tray.

A further object of the invention is to provide a tray frame having means for fastening the structure to a table top or highchair tray and adapted to support a removable cover of suitable plastic, which is extended rearwardly from the frame to form an integral bib portion.

2

A still further object of the invention is to provide a combined bib and tray device which is simple in construction and economical to manufacture, yet at the same time, is sufficiently rugged and durable to withstand the rough treatment usually received by children's equipment.

With the above and other objects in view, which will appear as the description proceeds, my invention consists in the novel features herein set forth, illustrated in the accompanying drawings and more particularly pointed out in the appended claims.

Referring to the drawings in which numerals of like character designate similar parts throughout the several views:

Fig. 1 is a perspective view showing the relationship of the combined bib and auxiliary tray, to the main tray of a child's highchair;

Fig. 2 is a top plan view of the device;

Fig. 3 is a longitudinal sectional view taken on line 3—3 of Fig. 2;

Fig. 4 is an enlarged perspective view of the supporting frame for the auxiliary tray;

Fig. 5 is an enlarged fragmentary sectional view showing the preferred form of inflatable side wall for the auxiliary tray; and

Fig. 6 is a similar view showing one modified form of inflatable side wall.

Referring first to the supporting frame generally indicated by the numeral 10 and best seen in Fig. 4, it will be noted that this structure preferably consists of a single wire, bent to the desired shape to form a substantially semi-circular cover support 11, connected at its rear end by a transverse cross-bar 12 and an integral spring clamp member 13 lying in a lower plane and adapted to engage beneath a highchair tray or table, as will later appear.

Following the contour of the frame 10 and starting at the point 14 on Fig. 4, it will be seen that the wire extends in a straight line for a predetermined distance where it is bent at 15 to form the substantially semi-circular cover supporting portion 11 which terminates at the point 16, where the wire is bent at an angle to form a continuation of the cross-bar 12. Adjacent the starting point 14, the wire is bent downwardly at right angles as at 17 and then forwardly and upwardly at an angle as at

18 to form one leg of the clamp member 13. From the leg 18 the wire is bent again at right angles to form the cross member 13 of the clamp and terminates at its opposite end in a second angular leg 19 which is bent upwardly as at 20 for connection to the cross-bar 12 of the frame.

The extremities of the single wire are butt-welded at the starting point 14 and at 21 where the leg 19 joins the cross-bar 12.

If desired to facilitate the attachment of a retaining strap, the intermediate portion of the cross member of the clamp 13 may be offset as at 22 to form a strap receiving clearance or recess.

In the preferred form of the invention illustrated in Figs. 1—5 of the drawings, a tray cover proper 23 is formed of a sheet of flexible plastic material, cut to conform substantially to the contour of the tray 24 of a conventional highchair. The forward arcuate edge of the cover 23 overlies the semi-circular supporting portion 11 of the frame 10 and is secured thereto in a manner to be described, while the rear extremity of the cover is extended to form an integral bib portion 25 having bifurcated end 26 to embrace the child's neck and a suitable

snap fastener arrangement 27 for securing the bib in place.

The forward edge of the tray cover proper 23 is bounded by an upstanding, tubular cell 28 formed of air-tight plastic material and shaped in plan profile to conform to the contour of the supporting portion 11 of the frame 10. In this form of the invention, the cell 28 is circular in cross-section as shown in Fig. 5 and is preferably formed of a single sheet of plastic material, closed on the underside of the cell by heat sealing as at 29. 10 One longitudinal edge of the sheet is extended to form a flap 30 which overlies the frame 10 and is adapted to be connected to the underside of the cover 23 by one or more snap fasteners 31. In other words, the base of the flap portion 30 overlaps the edge of the cover 23 which embraces the frame 10 and is heat-sealed thereto to form an integral structure with the cover 23, the entire assembly being removable from the frame by virtue of the snap fasteners 31.

The ends of the tubular cell are closed as at 32 and the side edges of the bib portion 25 are turned upwardly to form wings 33 which are joined to the closed ends 32 of the cell 28 by heat-sealing as at 34. The wings 33 thereby form substantially continuations of the inflatable side walls of the cover 23, formed by the upstanding tubular cell 28, the wings gradually tapering toward the neck receiving end of the bib 25 as will be seen from Figs. 2 and 3. Thus, when the combined tray cover and bib are in use, with the bifurcated end 26 engaging a child's neck, these two components form an integral receptacle, completely surrounding the area immediately in front of the child.

The tray cover and frame are secured in place on the conventional highchair tray 24 by means of the snap-on clamp 13 which as will be seen from Fig. 3, underlies the lower surface of the tray 24 and engages the latter with sufficient tension to prevent displacement of the frame and tray cover. As an added precaution against displacement, a centrally disposed retaining strap 35 is preferably secured to the underside of the cell 28 by heat-sealing as at 36, its opposite end being looped around the off-set portion 22 of the cross-member of the clamp 13 and secured to itself by a snap fastener 37. The strap 35 engaging the forward edge of the tray 24 and being secured to the clamp 13 which engages the rear edge of the tray, prevents either lateral or vertical displacement of the frame and tray cover.

At a suitable point on the side wall of the cell 28, there is provided a valve member 38 of conventional form, by means of which the cell 28 may be either inflated or collapsed. When in inflated condition, it will be apparent that the cell 28 will maintain a relatively firm upstanding position which together with the integral wing portions 33 of the bib will serve to effectively prevent the spilling of food from the tray or the knocking of toys onto the floor.

At the junction of the side wings 33 and the inflatable cell 28, it may be desirable to provide reinforcing strips 39 which are heat-sealed to the outer surfaces of these elements.

Turning now to the modified form of the invention shown in Fig. 6, it may be stated that this is basically the same as that just described, with the exception of the cross-sectional shape of the inflatable cell or side wall and the method of securing the same to the cover proper.

As will be seen from Fig. 6, the modified cell 28a is substantially elliptical in cross-section and the thickness of its side walls is gradually increased as at 40, so that their central portions are thicker than their upper and lower extremities. By gradually thickening the central portions of these opposed walls, the inflated tube 28a is enabled to maintain the desired shape to provide an upwardly and outwardly flaring wall bounding the outer edge of the cover 23.

As in the case of the preferred form of the invention,

the inflatable cell 28a is formed of a single piece of air-tight plastic material with its edges closed and heat-sealed as at 41. In this form, the bounding edge of the cover 23 is looped over upon itself to form a sleeve 42 for receiving the wire frame 10 and a reinforcing strip 43 overlaps and is heat-sealed to the adjacent portion of the cell 28a and the cover 23. The retaining strap 35 is heat-sealed between the edge of the cell 28a and the adjacent portion of the wire retaining sleeve 42.

It will be apparent that a combined bib and auxiliary tray made in accordance with this invention not only provides an effective means for preventing the spilling of food during the feeding of an infant and affords a sizable receptacle or basin for confining toys and other articles within a predetermined area, but it readily lends itself to many adaptations. While I have described the structure as a cover and auxiliary tray, it will be understood that in some instances this combination may be used without a main supporting tray and thus serve as the tray itself.

The integral structure of the bib and tray cover and the complete absence of stitches and seams renders the device far more sanitary and provides a much neater appearance than would otherwise be the case.

Furthermore, the collapsible feature facilitates the packing and storing of the device and from a merchandising standpoint, it presents a more compact package.

From the foregoing, it is believed that my invention may be readily understood by those skilled in the art without further description, it being borne in mind that numerous changes may be made in the details of construction without departing from the spirit of the invention as set forth in the following claims.

I claim:

1. A combined collapsible infant's bib and tray, comprising an open frame adapted to rest on a flat support, a separable cover of flexible material extending across said frame to form a bottom, an envelope of flexible material at least partially bounding the underside of said bottom for removably receiving said frame, the front and sides of said cover adjacent said bottom being bounded by an upstanding wall consisting of an inflatable cell terminating in closed ends on opposite sides of said bottom, the unbounded rear portion of said cover being extended to form an integral bib, the side edges of said bib being turned upwardly to form side wings, respectively contiguous with the closed ends of said cell, means for securing the extremity of said bib around a child's neck, and means formed integrally with said frame for anchoring the latter to said flat support.

2. A combined collapsible infant's bib and tray comprising a tray portion having a bottom of flexible material, the front and sides of said bottom being bounded by an upstanding wall consisting of an inflatable cell, terminating in closed ends on opposite sides of the rear of said bottom, the unbounded rear portion of said bottom being extended to form an integral bib terminating in a neck-receiving end, the side edges of said bib being turned upwardly to form side wings, respectively contiguous with the closed ends of said cell and gradually tapering toward said neck-receiving end, and means for securing said bib around a child's neck.

3. A combined collapsible infant's bib and tray comprising a tray portion having a bottom of flexible plastic material, the front and sides of said bottom being bounded by an upstanding wall consisting of an inflatable plastic cell, terminating in closed ends on opposite sides of the rear of said bottom, the unbounded rear portion of said bottom being extended to form an integral bib terminating in a neck-receiving end, the side edges of said bib being turned upwardly to form side wings, respectively contiguous with the closed ends of said cell and gradually tapering toward said neck-receiving end, and means for securing said bib around a child's neck.

75

4. A combined infant's bib and tray as claimed in claim 3, wherein said cell is circular in cross-sectional profile.

5. A combined infant's bib and tray as claimed in claim 3, wherein said cell is elliptical in cross-sectional profile.

6. A combined infant's bib and tray as claimed in claim 5, wherein the side walls of said elliptical cell are thickened centrally to add vertical support and shape retention.
